DESIGN FOR AN INTERLOCKING POKER CHIP

Cecil B. Woofter, St. Paul, Minn., assignor to
Brown & Bigelow, St. Paul, Minn.

Application January 2, 1947, Serial No. 135,884

Term of patent 14 years

(Cl. D34—5)

To all whom it may concern:

Be it known that I, Cecil B. Woofter, a citizen of the United States, residing in St. Paul, county of Ramsey, and State of Minnesota, have invented a new, original, and ornamental Design for an Interlocking Poker Chip, for which the following is a specification, reference being had to the accompanying drawings, forming part thereof.

Figure 1 is a plan view of an interlocking poker chip showing my new design.

Figure 2 is a plan view of the opposite side of my poker chip.

Figure 3 is an edge view of my poker chip.

Figure 4 is a section on the line 3—3 of Figure 1.

I claim:

The ornamental design for an interlocking poker chip, as shown.

CECIL B. WOOFTER.
